UNITED STATES PATENT OFFICE.

LOUIS C. NICHOLS, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

TRANSFORMER.

1,140,843.

Specification of Letters Patent. Patented May 25, 1915.

Application filed July 12, 1909. Serial No. 507,213.

To all whom it may concern:

Be it known that I, LOUIS C. NICHOLS, a citizen of the United States, residing at Milwaukee, in the county of Milwaukee and State of Wisconsin, have invented certain new and useful improvements in Transformers, of which the following is a full, clear, and exact specification.

My invention relates to electrical apparatus such as transformers and the object of my invention is to ventilate and cool such apparatus in a simple and effective manner.

This invention consists in certain novel details of construction and arrangement of parts to be described in the following specification and set forth in the appended claims.

In the accompanying drawings Figure 1 is a sectional view of a transformer equipped with my invention; and Fig. 2 is a top view 20 of the same transformer with the cover removed.

Referring to the figures of the drawing, 10 represents a base upon which is mounted a transformer inclosed in a casing having a main shell 11, a bottom 12 and cover 13. Located within this casing is a tank or baffle 14 which is secured to the bottom of said casing. Inside of the tank 14 is a frame 15 upon which is supported a laminated core 16 comprising two parts. High and low voltage windings 17 and 18 respectively are subdivided into a number of thin flat coils which present a large cooling surface, and the coils of said windings are wound upon said core. The coils are separated from each other forming spaces through which a fluid may pass to maintain the coils in a cool and economical operating condition. Leads 19 and 20 of the 30 coils are supported on terminal beams 21 which are provided with means for making electrical connections for said leads. The leads 22 are surrounded by insulating material 23 and pass through the cover 13 of the transformer casing and also through bushings 24 secured to said cover. The frame 15 is reinforced by means of bolts 25 which retain the laminæ of the core in a fixed position, and two or more of the bolts 25 are provided with eyes through which hooks may pass to remove the transformer proper from the casing without disturbing any of the other parts.

Located between the main shell 11 of the transformer casing and the tank 14 is a coil

consisting of several turns of pipe which extends circumferentially around said tank. This coil 26 is provided with an inlet 27 and an outlet 28, and is filled with a circulating cooling fluid such as water. The coil is held in position by means of supporting members 28^a which are secured to the shell 11 of the casing. The tank is filled with a fluid which is forced through the spaces between adjacent coils, between the coils and the core, and between the transformer and the tank, by means of a pump 29 exterior to the transformer casing. This pump is provided with a pipe 30 which passes through the casing of the transformer and through the tank 14, and is also provided with another pipe 31 which leads from the transformer casing to said pump. An insulating fluid, such as oil, is forced, by means of the pump, through the pipe 30 and is directed by means of the baffle or tank 14 through the internal structure of the core and coils and then overflows at the top of the tank coming in contact with the coil 26 which is filled with a circulating fluid of low temperature, thus cooling the oil which has become heated. The overflowing oil then passes down between the main shell of the transformer casing and the tank returning to the pump through the pipe 31. The oil in the transformer is maintained at a level indicated by the line O—O in Fig. 1. The oil which is heated to a certain extent while passing through the core and coil structure is cooled rapidly when it comes in contact with the coil containing the circulating cold water. By means of this pump a continual circulation of oil is kept up maintaining the transformer in practically a cool and economical operating condition.

It is obvious that there may be many modifications of the precise arrangement here shown and described, and I aim in my claims to cover all modifications which do not involve a departure from the spirit and scope of my invention.

What I claim as new is:—

1. The combination of a transformer comprising a core, coils mounted on said core with spaces between said coils and between said coils and said core, a tank filled with a fluid and surrounding said core and coils, means for maintaining a fluid circulation through said transformer, a casing inclosing said tank and spaced therefrom, and means

between said casing and said tank for cooling said fluid, which is forced by said circulating means into said tank, through said spaces, over the top of said tank, coming 5 in contact with said cooling means, and passing down between said tank and said casing into said circulating means.

2. The combination of electrical apparatus, a casing inclosing said apparatus, a 10 fluid in which said apparatus is immersed means inside said casing for cooling said fluid, and means for causing a circulation of said fluid through said electrical apparatus and into contact with said cooling means, 15 said means for causing circulation of said insulating fluid being between said cooling means and said electrical apparatus to receive fluid that has passed from said electrical apparatus and into contact with said 20 cooling means and to force said cooled fluid into contact with said electrical apparatus. 3. The combination of electrical apparatus, a casing inclosing said apparatus, insulating fluid in which said apparatus is immersed, means inside said casing for cooling 25 said insulating fluid comprising a coil through which a cooling fluid flows, said cooling fluid being admitted to said coil at the lower end thereof and leaving said coil at the upper end thereof, and means for 30 at the upper end thereof, and means for

forcing said insulating fluid through said apparatus and into contact with said cooling means said forcing means receiving fluid from the effective zone of said cooling means and forcing said fluid into contact with said 35 apparatus.

4. The combination of electrical apparatus, a tank filled with insulating fluid surrounding said electrical apparatus, a casing inclosing said tank, means between said casing and said tank for cooling said insulating fluid and comprising a coil through which a cooling fluid flows, said cooling fluid being admitted to said coil at the lower 40 end thereof and leaving said coil at the upper end thereof, and means for causing a circulation of said insulating fluid through said apparatus and into contact with said cooling means, said insulating fluid as it passes from said electrical apparatus to said 45 coil coming into contact with the upper portion of said coil and passing to the lower portion on its way to the circulation causing means.

In testimony whereof I affix my signature, in the presence of two witnesses.

LOUIS C. NICHOLS.
